SWING

William R. McGowen, Pittsburgh, Pa., assignor
to The McKay Company, Pittsburgh, Pa., a
corporation of Pennsylvania

Application October 27, 1932, Serial No. 639,795

4 Claims. (Cl. 5—124)

My invention relates to swings and more particularly to those of the glider type.

One object of my invention is to provide a swing or glider of such form that it has smoother movement than various types of swings heretofore produced.

Another object of my invention is to provide a swing wherein friction such as results in squeaking is avoided.

10 Still another object of my invention is to provide a swing wherein there is more effective resistance to side sway than in swings of various other types.

One form which my invention may take is shown 15 in the accompanying drawing wherein Figure 1 is a face view of the swing, and Fig. 2 is an end elevational view thereof.

The swing is shown as mounted upon a stationary support that comprises end frames, each of 20 which has a base bar 4 and uprights or posts 5. The base bars are connected by a tie bar 6 that is secured in place at its ends by bolts 7, the tie bar being curled at its ends to form eyes through which the bolts 7 extend. The bolts 7 also extend 25 through the lower end of a brace bar or pair of brace bars 8 of V form, so that such bars 8 will serve as trusses.

The upper ends of the brace bars are bolted or riveted to the legs 5, and a top rail 9 is also bolted 30 to the upper ends of the posts 5. The mid portion of each rail 9 is depressed relative to its end portions which are downturned, for a reason to be hereinafter explained.

35 A seat frame is suspended from the stationary rails 9 by means of spring steel strips or other flexible bars 10, placed at each corner of the structure. The seat structure proper consists of a pair of arm rails 11 which are curled at their upper ends to form eyes for the reception of a cross bar 12 whose ends are detachably secured to the upper ends of the arm rails 11 in any suitable 40 manner, as for instance, one of the ways shown in my copending application No. 575,761, filed Nov. 18, 1931 now Patent No. 1,936,459.

45 The forward ends of the side arms 11 are bent downwardly and bolted to front legs 13, the upper ends of said legs being curled to form eyes for the reception of a detachably connected cross bar 50 14. A canvas or similar strip 15 has its ends looped around the cross bars 12 and 14 and fastened in place, and a seat cushion 16 is placed on the seating strip 15.

Rear legs 17 have their upper ends connected to 55 the horizontal portions of the arm bars 11 and

are braced with respect to the front legs by means of tie rods 18.

The legs 13 and 17 are bent laterally at their lower ends as shown more clearly in Fig. 1, and are respectively rigidly secured to the lower ends 60 of the hanger straps 10, the upper ends of said straps being similarly rigidly secured to the ends of the bars 9.

Depression of the mid-portion of the top rails 9 avoids interference with a sitter's arm which rests 65 on the horizontal portions of the rails 11, while the bending up of the ends of the top rails permits the use of longer hanger strips 10 than would be the case if the top rails 9 were disposed entirely in a plane below the arm rests 11.

70 I have found that the use of spring metal straps 10 as hangers produces a smoother swinging action than chains or pivoted hangers, besides which, squeaking noises are avoided. When the swing is set in motion, the springs 10 are placed 75 under tension at each end of its path of oscillation, so that they exert a push or thrust tending to start movement of the swing in the opposite direction. In the ordinary type of swing, return movement is delayed somewhat, because 80 such movement is dependent entirely upon the action of gravity, unless the operator employs manual force. This is, of course, particularly true at the end of the backward movement of the swing, at which stage no means are com- 85 monly provided for the exertion of manual force.

Another advantage of the springs strips 10 is that, being disposed in planes parallel to the face of the structure, they resist end sway of the swing even under unbalanced weight.

80 The stationary frame structure can be readily disassembled and packed for shipment or storage by removing the bolts 7 and certain of the bolts which secure the steel strips 10 in place, to thereby disassemble the end frames and the tie bar 95 6. The seat structure can be disassembled by disconnecting the cross bars 12 and 14 from the side arms and legs of the seat.

I claim as my invention:—

1. Swing structure comprising stationary end 100 frames, a seat disposed in a generally horizontal plane approximately midway between the upper and lower edges of said frames, a member carried by each corner of the seat and extending downwardly to a point adjacent to, but above, 105 the bottom portions of the end frames, and vertically-extending strap-like hangers each having its lower end rigidly connected to the lower end of one of said members and its upper end rigidly connected to a top portion of the end frames, the 110

hangers being of flat spring material and disposed in planes approximately parallel to the front of the seat.

2. Swing structure comprising stationary end frames; a seat disposed in a generally horizontal plane approximately midway between the upper and lower edges of said frames, a leg member carried by each corner of the seat and extending downwardly to a point adjacent to, but above, the bottom portions of the end frames, and vertically-extending strap-like hangers each having its lower end rigidly connected to a leg member and its upper end rigidly connected to a top portion of the end frames, the hangers being of flat spring material and disposed in planes approximately parallel to the front of the seat, and the lower ends of the legs being laterally turned at their points of connection to the hangers, so that each pair of front and rear hangers will be disposed in the plane of its associated end frame.

3. Swing structure comprising stationary end

frames, a seat disposed between the frames and having an arm rest at each end thereof, a member at each corner of the seat and extending downwardly a distance not substantially less than the distance between the seat and the arm rest, and vertically-extending strap-like hangers of spring material, each rigidly connected at its lower end to one of said members, and at its upper end rigidly connected to an end frame at a point not materially lower than the adjacent arm rest.

4. Swing structure comprising stationary end frames, a seat disposed in a generally horizontal plane and having members extending downwardly to points adjacent to, but above the bottom portions of the end frames, and vertically-extending strap-like hangers of spring material each having its lower end rigidly connected to the lower end of one of said members and its upper end rigidly connected to an end frame at a point which is substantially higher than the plane of the seat.
